UNITED STATES PATENT OFFICE

LAGAR R. CULVER, OF LOS ANGELES, CALIFORNIA, ASSIGNOR OF ONE-HALF TO JOHN W. PRILLAMAN AND ELLA F. PRILLAMAN, OF VISTA, CALIFORNIA

POWER-DIPPER DOOR-LATCH RELEASE

Application filed January 23, 1929. Serial No. 334,519.

My invention relates generally to power shovels, particularly those of the gas-air type, and more specifically to means for releasing the latch that normally holds the door of the dipper in closed position, and my present invention is an improvement upon the power dipper door latch trip set forth in my co-pending application for U. S. Letters Patent filed August 11, 1928, Sr. No. 299,058.

10 The principal objects of my present invention are to generally improve upon and simplify the construction of the dipper door latch releasing means disclosed in my aforesaid patent application, to provide a latch tripping device that is capable of being applied to practically all makes of shovels without altering the construction thereof or involving special machine work on the parts thereof, and, further, to provide 15 a latch releasing device that is relatively simple in construction, inexpensive of manufacture, capable of being easily and quickly applied to the shovel for use, and which is strong and durable in construction and positive and efficient in operation.

It will be understood that the dipper door latches of power shovels are generally actuated by means of a cable, a portion of which winds upon a drum, and it is one of the objects of my invention to provide simple and efficient means that will at all times and under all conditions take up the slack in the latch releasing cable and yet permit the dipper to be manipulated while being filled without drawing the cable sufficiently taut to release the dipper door latch and further to provide simple and efficient means under control of a foot pedal for actuating the latch releasing means, and further to provide a brake that cooperates with the cable carrying drum for preventing the latch actuating cable from unwinding when the power shovel is reversed or moved rearwardly.

With the foregoing and other objects in view, my invention consists in certain novel features of construction and arrangement of parts that will hereinafter be more fully described and claimed and illustrated in the accompanying drawings, in which:

Fig. 1 is a side elevational view of a gas-air

power shovel and showing my improved dipper door latch releasing means applied thereto.

Fig. 2 is a side elevational view of my improved dipper door latch releasing means with parts broken away and in section.

Fig. 3 is an elevational view of the lever that is utilized for applying pressure to the friction disks that cooperate with the cable carrying drum.

Fig. 4 is a vertical section taken approximately on the line 4—4 of Fig. 2.

Fig. 5 is a front elevational view of the pedal that is utilized for actuating the latch releasing means.

Fig. 6 is a side elevational view of the pedal.

Referring by numerals to the accompanying drawings which illustrate a practical embodiment of my invention, 10 designates a cab of a gas-air shovel, which cab is generally mounted on a caterpillar traction base 11, said cab enclosing the engine and the greater portion of the operating parts of the shovel including the main drum gear wheel 12.

Projecting from the front of the cab is a boom 13 upon which is arranged for operation in the usual manner, the dipper stick 14 carrying at its lower end the dipper or shovel 15, and the latter being provided with the usual drop door 16 that is normally retained in closed position by a latch 17.

Secured to the latch 17 is one end of a cable 18 that extends into the cab 10 to my improved latch releasing means, and which cable is conveniently supported on the boom 13 by a pulley such as 19.

Arranged in the front portion of the cab is the operator's seat 20, in front of which is positioned the usual operating or control levers 21, and arranged on the floor of the cab is the usual main control valve 22.

Leading from this main valve to the transmission ram is a fluid pressure pipe 23 and leading from said valve to the reverse ram is a fluid pressure pipe 24.

The latch releasing means contemplated by my invention is conveniently supported upon a suitable bracket 25 that is detachably secured in any suitable manner, preferably by

means of J-bolts 26, to a transverse beam that forms a part of the gantry frame of the machine and said bracket being positioned just above the main drum gear wheel 12.

5 Formed in the bracket 25 is a horizontally disposed bearing 27 in which is journaled a short shaft 28, and secured to one end thereof is a small gear wheel 29 that meshes with the main drum gear wheel 12, and which latter, it will be understood, rotates constantly while the shovel is in operation.

10 The end of shaft 28 opposite the end that carries the gear wheel 29 projects a short distance beyond the bearing 27 and mounted on 15 keys or feathers 30 on said projecting end are the hub portions of a pair of disks 31.

15 These disks are mounted so that they slide toward and away from each other upon their keys or feathers, and they are retained on 20 the shaft by a nut 32 that is secured on the end of the shaft and by a thrust bearing 33 that is mounted on the shaft just beyond the inner one of the pair of disks.

25 Arranged to rotate freely upon the hubs of the disks 31 and between the same is a drum or pulley 34 upon which is wound a considerable portion of the cable 18 and the inner end of said cable being secured to the periphery of said drum, as illustrated in Fig. 2.

30 Carried by the inner faces of the outer portions of the disks 31 are clutch facings 35 that are adapted to engage the outer faces of the drum or pulley 34.

35 Formed in the end of shaft 28 on which the disks and cable receiving drum are mounted is an axle bore 36 on the outer end of which is seated a grease cup 37 and leading from the inner end of said bore outwardly through the shaft 28 are axially disposed ducts 38 that 40 carry the grease or lubricant from the chamber 36 to the periphery of the shaft upon which the hubs of the disks 31 are mounted.

45 Formed through the disks 31 just inside those portions that carry the clutch facings 35 are lubricant discharge ducts or openings 39 having inclined bottoms, and these openings are arranged so that lubricant passing outwardly from the hub portions of the disks will discharge to the outer faces of the outer portions of said disks instead of passing outwardly between said disks and the drum 34, in which latter event the clutch facings would become impregnated with lubricant and they would soon lose their efficiency.

50 Depending from the bearing 27 is an arm 40 and secured thereto is a bracket 41. Formed in said arm and bracket are coinciding apertures in which is seated a bushing 42 and passing through the latter is a push rod 43, the inner end thereof being arranged for sliding movement in the inner portion of the bracket 41.

55 Mounted on a threaded portion of rod 43 is a nut 44, and interposed between said nut and the inner portion of bracket 41 is an expansive coil spring 45. The outer end of rod 43 passes through the lower portion of a Y-shaped lever 46, the latter being fulcrumed on a pin or bolt 47 that passes through ears 48 that project from the outer face of bracket 25 just above the bearing 27.

60 Formed on the outer face of the lever 46 to the sides of shaft 28 are lugs 49 that bear against the thrust bearing 33.

65 Mounted on the outer portion of push rod 43 is a nut 50 that bears against the rear face of the lower portion of lever 46.

70 Fulcrumed on the inner lower portion of bracket 41 is a bell crank 51 and the upturned short arm thereof bears against the inner end 80 of push rod 43.

75 Mounted on the floor of the cab directly in front of the operator's seat 20, and preferably directly above the shaft on which the control levers 21 are mounted, is a block 52 on which is fulcrumed a pedal 53 and fulcrumed on the block below the front portion of this pedal is a bell crank 54, one arm of which is connected by a link 55 to the foot pedal 53 in front of its fulcrum.

85 Clamped in any suitable manner to the opposite arm of the bell crank 54 is one end of a flexible member 56, preferably a section of piano wire, and the opposite end of this flexible member is clamped in any suitable manner to the long arm of the bell crank 51. This flexible member is enclosed in a flexible metal sheath or cable 56, one end of which is clamped to block 52 and the other end being secured to the lower portion of bracket 41.

90 Projecting outwardly from the lower portion of arm 40 is a rod 57 and carried thereby is a spool 58 that is positioned directly beneath the drum 34 and said spool serving as a guide for the cable as it winds on to and from said drum.

95 Projecting outwardly from the upper portion of bracket 25 is an arm 59 that terminates above the drum 34 and secured to said arm directly over the drum is a cylinder 60 within which is arranged for operation a piston 61.

100 Leading from the tube 24, which latter leads from the main control valve 22 to the reverse ram, to the upper end of the cylinder 60, is a fluid pressure pipe 62 and by virtue of this last mentioned pipe fluid pressure passes from the conduit 24 to the upper end of cylinder 60, at the same time that fluid pressure passes from the main control valve to the reverse ram.

105 Arranged for sliding movement through the ends of the bracket 59 are rods 63 and carried by the lower ends thereof is a brake shoe 64 that is adapted to bear on top of the coils of cable 18 that occupy the drum 34.

110 Arranged on the upper portions of the rods 63 are expansive coil springs 65, the upper ends of which bear against washers or nuts 66 that are secured on the upper ends of said rods. These expansive springs yieldingly re-

sist the downward movement of the rods 63 that carry the brake shoe 64, and under normal conditions said springs hold the rods and the brake shoe at their upper limit of movement.

5 While the shovel is in operation, the main drum gear wheel 12 operates continuously and as pinion 29 meshes with the main gear wheel, shaft 18 will be constantly rotated, 16 and the speed of rotation will be relatively high due to the relative sizes of the main drive wheel and the gear wheel 29.

Inasmuch as the disks 31 are keyed to shaft 28 said disks will rotate constantly but 15 until clamping pressure is applied to said disks they will not impart rotary motion to the cable drum 34. Thus as the dipper 15 is moved downwardly and outwardly while being filled the cable 18 will unwind from the 20 drum 34 inasmuch as the latter is free to rotate upon the hubs of the disks 31.

After the dipper has been elevated and it is desired to release the latch to permit the dipper door to open, the operator from his 25 position upon seat 20 actuates pedal 53 and through link 55 bell crank 54 is swung upon its fulcrum so as to pull the flexible member 55 through its sheath or housing, thereby actuating bell crank 51 so as to move push rod 43 outwardly through bracket 41 and arm 40.

As a result of this operation the lower end 30 of lever 46 is moved toward the drum 34 and the lugs 49 engaging thrust bearing 33 moves the inner one of the friction disks 31 against the corresponding face of drum 34, and as 35 the outer one of the friction disks is held against movement by the nut 32 the winding drum will be engaged by the clutch facings 35 so that said drum will be picked up and 40 rotated with the constantly rotating friction disks 31. As drum 34 is thus rotated, cable 18 will be wound upon said drum, thereby exerting pull upon the latch 17 so as to release the dipper door, and when such operation has 45 been effected the operator releases pressure on the pedal 53, which action relieves the pressure applied to the friction disks by the lever 46, thereby breaking the driving connection between said friction disks and the 50 cable carrying drum 34 so that the latter ceases to rotate.

The tension of spring 45 is such as to produce sufficient pressure on lever 46 and the friction disks to engage the winding drum 55 and cause the same to rotate and take up the slack in cable 18, but the pressure of said spring is insufficient to bring about a rotation of the cable drum and cause the cable that winds thereonto to release the latch 17.

55 In other words the latch releasing operation is only accomplished by actuation of the pedal 53 and actuation of the parts connected and controlled thereby.

The flexible member 55 and its sheath 56 provide a strong and substantial connection

between the bell crank 54 that is actuated by the pedal and the bell crank 52 that is connected to said flexible member and which imparts movement directly to the push rod 43.

When the proper one of the control levers 70 21 is manipulated so as to actuate the main control valve 22 and permit fluid pressure to pass through pipe 24 to the reverse ram fluid pressure will at the same time pass through pipe 62 into the upper end of cylinder 60, 75 thereby moving piston 61 downwardly and in turn the brake shoe 64 will be moved downwardly to engage the coils of cable that is wound upon drum 34, and such action prevents the cable on said drum from unwinding while the shovel is being reversed or moved rearwardly.

When the fluid pressure is cut off to cylinder 60 the springs 65 will act to instantly elevate the brake shoe 64.

80 Thus it will be seen that I have provided relatively simple, practical and inexpensive means for positively controlling the operation of the drum that carries the cable that actuates the dipper door latch and which means is strong and durable in structure and capable of being readily applied to all makes of gasoline or gas air shovels without special machine work or without requiring special castings or extraneous parts.

85 The pedal that controls the operation of the latch releasing means is conveniently located immediately in front of and below the operator's seat and as the latch releasing means is directly connected to the main drum gear wheel of the shovel by a relatively small gear or pinion, said latch releasing means is capable of being positively actuated at all times and due to the relative sizes of the main gear wheel and the pinion the operation of the 90 latch releasing device is comparatively rapid.

100 The nut 44 provides means whereby the tension of spring 45 may be accurately regulated and nut 50 provides means for adjusting the position of the lower end of lever 46 relative to the push rod, and as a result of these 105 two adjustments a very accurate regulation of the normal tension between the friction disks and the cable receiving drum may be obtained.

110 It will be understood that minor changes in the size, form and construction of the various parts of my improved power dipper door latch releasing device may be made and substituted for those herein shown and described 115 without departing from the spirit of my invention, the scope of which is set forth in the appended claims.

I claim as my invention:

120 1. In a power dipper door latch releasing device, a rotatably mounted shaft, a winding drum loosely mounted on said shaft, a cable secured to and adapted to wind onto said drum, which cable is connected to the dipper door latch of the shovel with which the de- 130

vice is associated, means providing a slip drive connection between said drum and shaft, whereby said drum tends to rotate to wind the cable thereon, and maintain the same under a tension insufficient to actuate the latch, an arcuate brake shoe arranged for operation adjacent to said drum, means for moving said brake shoe into frictional engagement with the cable on said drum, and 10 pedally actuated means for providing a greater frictional connection between the drum and shaft whereby tension is applied to the cable sufficient to release the door latch.

2. The combination with a power shovel and the latch of the dipper door associated therewith, of a trip cable connected to said latch, a drum on which said trip cable is wound, a constantly rotating shaft carrying said drum, means for imparting the rotation 15 of the shaft to said drum to keep slack out of the cable, but not sufficiently to positively actuate the cable to trip the dipper, an arcuate brake shoe arranged for operation adjacent to said drum, means for moving said 20 brake shoe into frictional engagement with the cable on said drum and pedally actuated means for imparting rotation of the shaft to the drum to wind the cable thereonto and to trip the dipper door latch.

30 3. The combination with a power shovel, its main control valve and the latch of the dipper door that is associated with said shovel, of a constantly rotating shaft, a cable secured to and adapted to wind onto said shaft, which 35 cable is connected to the dipper door latch, a cylinder, a piston arranged for operation therein, a brake shoe arranged between said piston and the coils of the cable carried by said drum, and a fluid pressure conduit leading from the main control valve to said cylinder.

40 4. In a power shovel dipper door latch release, the combination of a drum, a cable secured to and adapted to wind onto said drum, which cable is connected to the dipper door latch, a cylinder positioned adjacent to the periphery of the drum, a piston arranged for operation within said cylinder, means for admitting fluid pressure to said cylinder, and 45 a brake shoe adapted to be engaged by the piston and moved into engagement with the coils of the cable on said drum.

5. In a power shovel dipper door latch release, the combination of a drum, a cable secured to and adapted to wind onto said drum, which cable is connected to the dipper door latch, a cylinder positioned adjacent to the periphery of the drum, a piston arranged for operation within said cylinder, means for admitting fluid pressure to said cylinder, a brake shoe adapted to be engaged by the piston and moved into engagement with the coils of the cable on said drum, and means associated with 55 said brake shoe for withdrawing the same from engagement with the coils of the cable.

6. The combination with a power shovel, its dipper door latch, its main control valve and the pipe leading from said valve to the reverse ram, of a drum, a cable secured to and adapted to wind onto said drum, which cable is connected to the dipper door latch, a constantly rotating shaft, pedally controlled means for imparting the rotation of said shaft to said drum, a cylinder disposed adjacent to said drum, a piston within said cylinder, a 70 brake shoe adapted to be engaged by said piston and moved into engagement with the coils of cable on the drum, and a fluid pressure conduit leading from the pipe that leads from the main control valve to the reverse ram to said cylinder whereby the piston within said cylinder is actuated simultaneously with the actuation of the reverse ram.

7. In a power dipper door latch releasing device, a rotatably mounted shaft, a pair of friction disks carried by said shaft and adapted to rotate therewith and to move toward and away from each other, a drum mounted for independent rotary movement between the said disks, a cable secured to and adapted to wind onto said drum, which cable is connected to the dipper door latch, means for moving one of said friction disks toward the other to frictionally engage said drum, a pedal, flexible connections between said pedal and the friction disk actuating means, an arcuate brake shoe arranged adjacent to said drum and means for moving said brake shoe into frictional engagement with the cable on said drum. 85

8. The combination with a power shovel and the latch of the dipper door associated therewith, of a trip cable connected to said latch, a drum on which said trip cable is wound, a constantly rotating shaft carrying said drum, means for imparting the rotation of the shaft to said drum to keep slack out of the cable, but not sufficiently to positively actuate the cable to trip the dipper, pedally actuated means for imparting rotation of the shaft to the drum to wind the cable thereonto and to trip the dipper door latch, a portion of which pedally actuated means is adjustable in order to vary the normal degree of friction impressed on the cable receiving drum, an arcuate brake shoe arranged adjacent to said drum and means for moving said brake shoe into frictional engagement with the cable on said drum. 100

In testimony whereof I affix my signature. 120
LAGAR R. CULVER.
